United States Patent Office

Des. 212,796
Patented Nov. 19, 1968

212,796

RIBBON

James R. Hecht, 473 Franklin D. Roosevelt Drive,
New York, N.Y. 10002

Filed Mar. 20, 1967, Ser. No. 6,297

Term of patent 14 years

(Cl. D92—1)

The figure in the drawing is a plan view of a ribbon embodying my new design.

I claim:

The ornamental design for a ribbon, substantially as shown.
